ATTORNEY.

Patented Sept. 11, 1923.

1,467,456

UNITED STATES PATENT OFFICE.

EARL J. SILVIUS, OF SALEM, NEW HAMPSHIRE.

REVOLUBLE BUFFER.

Application filed July 5, 1921. Serial No. 482,530.

To all whom it may concern:

Be it known that I, EARL J. SILVIUS, a citizen of the United States, residing at Salem, in the county of Rockingham and State of New Hampshire, have invented 5 certain new and useful Improvements in Revoluble Buffers, of which the following is a specification.

This invention relates to buffers or bumpers for circular cars or tubs such as are used 10 in amusement devices of various kinds.

It is more particularly useful when attached to circular cars of the type such as shown in patents to Stock, Amusement device, No. 1,339,299, May 4, 1920, Stoehrer, Amusement apparatus, No. 1,373,108, March 15 29, 1921, and in my applications for patents pending herewith, No. 471,313, filed May 21, 1921, and No. 472,565, filed May 25, 1921, 20 provided with motive power and such as are used on a floor with a fence around it and intended for use by unskilled operators.

When two of these cars come together or when one strikes the fence, it is desirable 25 that it should not stop but should continue its course with as little delay and as little manual steering as possible.

I am aware that annular spring fenders and annular pneumatic tires have been used 30 on such cars, but my improvement consists broadly of a buffer, preferably of the pneumatic type, which is revoluble in a horizontal plane around the car.

It may also be used on such tubs as shown 35 in patent to Mangels, Amusement apparatus, No. 873,570, December 10, 1907, where the tub is intended to move in a chute or slide and to strike the sides thereof.

In the drawings, Fig. 1 is a plan view 40 showing part of the floor and fence of an amusement device, including one of the cars such as are used therein with my buffer attached.

Fig. 2 is an elevation, partly in section, 45 showing part of such a floor, fence, and car, with my preferred type of pneumatic buffer shown in section and attached thereto.

Fig. 3 is a sectional elevation of another 50 pneumatic buffer attached to such a car supported by a different type of bearings.

Fig. 4 is a plan view of a car or tub with a revoluble horizontal rim carrying spring buffers instead of a pneumatic tire.

Fig. 5 is a sectional elevation, similar to 55 Figs. 2 and 3, on the line 5—5 of Fig. 4.

In the drawings, A represents a floor around the whole or part of which is a protecting fence B so that the cars, of which one is shown at C, cannot run off. The type of car shown at C has freely swiveled 60 supporting rollers 9 which rest upon the floor, and a traction unit, indicated at D, comprising rollers 5, 5, which rest upon the floor and are freely swiveled so as to revolve on or with a short vertical shaft 3 which also 65 carries a transmission gear 6 through which power is applied from a motor indicated at 7. The rollers 9, 9, and 5, 5, support the car C and permit it to be moved in any direction manually or through power from 70 motor 7.

8 represents the floor which is shown as made of wood and of circular form, with a metal band 11 attached thereto by screws 12 for strength. The operator's seat is 75 represented by 10, and F represents a steering device including a wheel 70 and shaft 71 which passes through the floor and turns a sprocket 72, around which passes the chain 4 which also passes around another sprocket 80 73 whereby the motion of the wheel can be transmitted by the operator to the rollers 5, 5, whereby the car may be directed with more or less accuracy.

The above described features are substantially shown in the patents mentioned and in applications of mine now pending.

Referring to Fig. 1, when the car C is driven in the direction of the arrow toward fence B at a slight angle, there is a tendency for it to stick there unless it is provided with my horizontally revoluble buffer which I will now describe.

At suitable intervals around car C, disposed in a horizontal plane, I locate brackets L which support suitable bearings on and outside of which is revoluble an annular rim H which carries on its outside, a pneumatic tire of annular form indicated by K. This tire may be made up of an outer 100 shoe 20 with an inner tube 21 in a well known manner, and may have a thickened portion 22 to engage the flanges 32 on rim H.

Preferably, I revolubly support rim H in roller bearings shown in detail in Fig. 2.

Each bracket L comprises a top part 75 which rests against the outer edge of car C and is attached to band 11 by means of screws 77 and a supporting leg 76 attached to the bottom of floor 8 by means of screws, 110

such as 48, so as to project therefrom under the part 75 which it helps to support. The parts 75 and 76 together comprise the bracket L which also includes the roller bearings now to be described.

In a recess 40 in the part 75 is located a roller bearing, consisting of a sleeve 42 and spindle 43, which passes up through the top of part 75 and down through the part 76, 10 being held in position by the nuts 41. Against this roller bearing and the others arranged around the car bears the inside edge 33 of rim H.

Preferably also, in a recess 44 under the 15 top of part 75 and recess 49, in the upper part of leg 76, I locate top and bottom roller bearings each of which consists of a revolvable sleeve 45 carried by pin 46. By means of these roller bearings, the rim H and tire 20 K are so supported that they will move around the car and permit the car to roll along the fence B or to roll around another car with great facility. As shown in Fig. 3, I can omit the roller bearings and support a single tube pneumatic tire O in a 25 rim N which is itself supported in a groove 51, forming a projection from the annular metal bearing M which extends all around the car C and is attached thereto by means 30 of screws 52. This is shown as being reinforced underneath by means of brackets such as 53 attached under the car C by screws 54 and to bearing M by screws 55.

While I prefer a continuous pneumatic 35 tire structure, I may, as shown in Figs. 4 and 5, attach horizontally around the edge of car C by means of screws 61 annular

metallic bearing P around which the annular metallic rim R is revolvable. This rim R may be held in position by means of brackets or dogs 66 and 67, each having an overhang 64 or 65 to keep rim R in position, and each attached to car C by a screw 62 or 63.

Attached to rim R by means of screws 45 such as 60, are a plurality of bent springs S so arranged that they will extend outwardly therefrom and will therefore serve as buffers, they, together with rim R, being revolvable in a horizontal plane on the outside of bearing P.

I claim:

1. In an amusement apparatus, the combination with a car supported by rollers and having steering and propelling means, of roller bearings disposed in a horizontal plane thereabout, an annular rim revolvable on and outside said bearings, and a pneumatic tire carried outside thereof by said rim.

2. The combination with a car for amusement purposes, of roller bearings disposed in a horizontal plane thereabout, an annular rim revolvable on and outside said roller bearings, and a pneumatic tire carried outside thereof by said rim.

3. The combination with a car having bearings disposed in a horizontal plane thereabout, of an annular buffer revolvable on and outside of said bearings.

4. The combination with a car supported by rollers, of an annular buffer revolvable in a horizontal plane around said car.

EARL J. SILVIUS.
